UNITED STATES PATENT OFFICE.

HERBERT CORRAL, OF LEICESTER, ENGLAND, ASSIGNOR TO THE SINGER MANUFACTURING COMPANY, A CORPORATION OF NEW JERSEY.

BUTTON-SEWING MACHINE.

1,086,651.

Specification of Letters Patent.

Patented Feb. 10, 1914.

Application filed January 10, 1911. Serial No. 601,867.

To all whom it may concern:

Be it known that I, HERBERT CORRAL, a subject of the King of the United Kingdom of Great Britain and Ireland, residing at 5 Leicester, in the county of Leicester, England, have invented certain new and useful Improvements in Button-Sewing Machines, of which the following is a specification, reference being had therein to the accompanying drawings.

This invention relates to an improvement in button sewing machines adapted for sewing on what may be termed integral shank buttons, in which a projection is provided 15 upon the inner face of the head either pressed or molded thereon and suitably apertured to receive the fastening threads or formed of a tuft of cloth or other soft substance adapted to be penetrated by the needle carrying the fastening thread.

The invention has for its object to provide an effective and conveniently operated device for holding the buttons for the stitching operation.

25 In its preferred form, the improvement comprises a throat-plate formed in its upper face with a longitudinal slot connected at opposite sides respectively with a button-shank cavity affording the needle-hole and 30 a clamp-jaw receiving cavity, the latter being entered by an upturned lip constituting the clamp-jaw for the button-head and formed upon a transversely reciprocating spring-pressed slide-bar suitably journaled 35 upon the sewing machine work-plate and having a depending pin connected at one end with a rock-lever fulcrumed beneath the bed-plate and attached to one end of a reciprocating rod adapted to be engaged at 40 the other end by the depending arm of the presser - foot lifting angle-lever fulcrumed upon the bracket-arm of the machine. The presser - foot, whose operative face overlies the top of the throat-plate, is cut out correspondingly with the button-shank cavity of 45 the latter, and is fastened to the usual spring-pressed presser-bar adapted for operative engagement with the presser - foot lifting angle-lever, the actuation of the latter causing the simultaneous lifting of the 50 presser-bar for introduction and removal of the work and retraction of the button-clamp-jaw for release and introduction of the button. The button-holding means, as thus described, are preferably applied to an over-

seaming sewing machine having a jogging needle moving alternately in paths traversing and beyond the end of the button-shank, but it is obviously immaterial how the relative jogging movements between the button 60 and work and the stitch-forming mechanism be produced, as regards the present improvement.

In the accompanying drawings, Figure 1 is a rear side elevation of a sewing machine 65 embodying the present improvements, and Fig. 2 a bottom plan view of the same, the forward end portion of the bed-plate being omitted in both views. Fig. 3 is a sectional elevation representing the button-holder, the 70 needle and its lateral jogging means. Fig. 4 is a perspective view showing upon a larger scale the operative portions of the button-holder separated to receive a button and the folded work to which it is to be attached. 75 Fig. 5 is a perspective view of the molded perforate-shank button which the present improvement is adapted to accommodate.

The machine is constructed with the usual base 1 and overhanging bracket-arm 2 in 80 which is mounted the usual main-shaft provided with fast and loose pulleys 3 and 4 upon which the power belt is directed by means of the belt-shifter 5 of the stop-motion mechanism of usual or suitable construction. In the head of the bracket-arm is journaled the swinging needle-frame 6 in which is mounted the reciprocating needle-bar 7 carrying the jogging needle 8. The needle-bar frame 6 is pivotally connected 85 with one end of a pitman 9 adjustably attached at the other end to the groove segment lever 10 fulcrumed upon the bracket-arm at 10° and having a stud entering the cam-groove 11 of a disk 11 connected with 90 and driven at one-half the speed of the main-shaft from which the needle-bar derives its reciprocating movements. Coöperating with the needle in the production of overseam stitches is a well known form of 95 shuttle mounted for oscillation in a race-way in a plane parallel with the jogging movements of the needle. The bed-plate has the usual opening surrounding the needle-path, and has let into its upper face adjacent thereto the throat-plate 12 formed with apertures 13 for the fastening screws and having in its flat upper face the longitudinal button-head receiving slot 14 formed 100 at its opposite sides with the laterally ex- 105

110

tending button-shank cavity 15 affording a needle aperture 16 and the clamp-jaw receiving cavity 17. The cavity 17 of the throat-plate is partially closed by means of 5 a plate 18 secured in position by screws 19 and forming a closed channel for the reduced forward end portion 20 of a slide-bar 21 having at its extreme forward end the upturned lip 22 whose forward extremity 10 affords a clamp-jaw for engagement with the outer face of the button *b* whose opposite face is thereby pressed against the forward wall of the slot 14 in the throat-plate. The rearward portion of the slide-bar 21 is 15 guided by means of a strap 23 secured upon the bed-plate by screws 24, and has a longitudinal socket 25 entered by a pin 26 having its apertured head 27 secured by means of the screw 28 upon the bed-plate, a spring 20 29 being interposed between the inner end of said socket and the adjacent end of the pin 26 for pressing the slide-bar 21 normally 25 toward the throat-plate.

Depending from the rearward end of the 25 slide-bar 21 through an aperture 1* in the bed-plate is a stud 30 entering an aperture in the extremity of one arm 31 of a rock-lever having a boss 32 intermediate its ends journaled upon the fulcrum-screw 33 tapped 30 into the lower side of the base-plate, and carrying upon its oppositely extending arm 34 the stud-screw 35 embraced by the apertured forward end 36 of the reciprocating rod 37 journaled in a suitable bearing aperture 35 in the bracket 38 having apertures 39 for fastening screws 40 by means of which it is attached to the under side of the bed-plate.

The usual spring-pressed presser-bar 41 40 has attached to the reduced lower end by means of the fastening screw 42 the shank 43 of the presser-foot 44 which has at the inner edge the lateral cavity 45 similar in contour to the cavity 15 16 of the throat-plate and overlying the face of the latter adjacent said cavity. The presser-bar has the usual fixed collar provided with a backwardly extending arm 46 adapted for engagement by the forwardly projecting arm 45 of the presser-lifting angle-lever fulcrumed by means of the stud-screw 48 upon the back of the bracket-arm and having a depending arm 49 passing through a slot 50 in the bed-plate and moving in a path beneath the same embracing the rearward extremity of the reciprocating clamp-actuating rod 37. In practice, the angle-lever 47 49 receives its operative movements from engagement with its depending arm of the 55 curved bar 51 secured by means of the set-screw 52 in a boss 53 of the collar 54 which is fixed upon the transverse rock-shaft 55 mounted beneath the top of the work-supporting table and having an operative connection with a knee lever or treadle con-

trolled by the operator. The machine is also provided with the usual finger-lever 56 by means of which the presser may be lifted by hand independently of the angle-lever 47 49.

In the use of the machine, the rock-shaft 55 is operated to tilt the angle-lever 47 49, whereby the presser-bar is lifted to raise the presser-foot and the button-clamp jaw 22 is simultaneously retracted for admission of a 70 button, as represented in Fig. 4. A button *b* having been dropped by hand into the slot 14 with its edge resting upon the convergently inclined bottom portions of the latter, and the folded material *m* having been introduced beneath the presser-foot with its edge abutted against the adjacent end of the button-shank, the presser-lifting angle-lever is released, whereby the presser-foot descends under the action of the presser-bar 75 spring and rests upon the material adjacent the cavities 15 and 45, and at the same time the slide-bar 21 advances under the action of its spring 25 to engage the jaw 22 with the rounded outer face of the button which 80 is forcibly seated thereby against the opposite wall of the button-head slot 14 in the throat-plate and the adjacent edge of the presser-foot, as represented in Fig. 3. The stitch-forming mechanism being now set in 85 motion, the needle descends alternately through the button-shank eye and the folded edge of the material in the production of the fastening stitches. The predetermined number of stitches having been applied and the machine automatically stopped by the 90 automatic action of the stop-motion device, the presser-foot is lifted and the jaw 22 retracted for removal of the work or shifting of the latter preparatory to application of 95 the succeeding button. At the completion of a button-fastening operation, the work is opened out flat and the button occupies a position in the body of the material.

It will be obvious that the position of the 100 extremity of the button-shank, which affords a stop for the folded edge of the material in the stitching operation, will determine whether or not the needle will penetrate both faces of the material, and hence whether 105 the button is fastened by blind stitches or through-and-through stitches.

Having thus set forth the nature of the invention, what I claim herein is:—

1. In a sewing machine, the combination 110 with stitch-forming mechanism including a reciprocating needle, of a button-support formed with a button-head seat substantially parallel with the needle and with an adjacent button-shank cavity, a pressure member overlying said button-support adjacent said cavity and movable toward and from said support and substantially parallel with the needle, and a button-head clamp-jaw movable toward and from and transversely 115 120 125 130

of the button-head seat with which it co-
operates in holding the button-head.

2. In a sewing machine, the combination
with stitch-forming mechanism including a
reciprocating needle, of a button-support
5 formed with a button-head seat substan-
tially parallel with the needle and an adjac-
ent button-shank cavity, a pressure mem-
ber overlying and disposed in clamping re-
lation with said button-support adjacent
10 said cavity and at the side of the seat within
the range of movement of the needle, a
spring-actuated button-head clamp-jaw
movable toward and from and transversely
15 of the button-head seat, and means for re-
tracting said clamp-jaw in opposition to its
spring.

3. In a sewing machine, the combination
with stitch-forming mechanism including a
20 reciprocating needle, of a button-support
formed with a button-head seat substan-
tially parallel with the needle and an adjac-
ent button-shank cavity within the range of
movement of the needle, a pressure member
25 overlying and adapted to rest upon said but-
ton-support adjacent said cavity and formed
with a lateral recess above and in register
with the latter, a button-head clamp-jaw
movable toward and from and transversely
30 of the button-head seat, and means including
a common operative member for lifting said
pressure member and retracting the button-
head clamp-jaw.

4. In a sewing machine, the combination
35 with stitch-forming mechanism including a
reciprocating needle, of a throat-plate hav-
ing a longitudinal button-head receiving slot
with connected lateral oppositely disposed
button-shank cavity and clamp-jaw receiv-
40 ing cavity, a presser-foot formed at one side
with a button-shank recess in register with
the button-shank cavity of the throat-plate,
a slide-bar movable transversely of said slot
in the throat-plate and carrying a button-
45 head clamp-jaw entering the clamp-jaw re-

ceiving cavity of the throat-plate, and means
for lifting the presser-foot and retracting
said slide-bar.

5. In a sewing machine, the combination
with stitch-forming mechanism including a
reciprocating needle, of a button-support
50 formed with a button-head seat substan-
tially parallel with the needle and an adjac-
ent button-shank cavity, a pressure member
overlying said button-support adjacent said
cavity, a transversely movable spring-
55 pressed slide-bar carrying a button-head
clamp-jaw in register with said seat, a rock-
lever mounted upon a fixed fulcrum, an op-
erative connection between said slide-bar
and said rock-lever, an operating push-rod
60 connected with said rock-lever, an angle-
lever mounted upon a fixed fulcrum and
having one arm in operative relation with
the pressure member and another arm in op-
erative relation with said operating push-
65 rod for simultaneously operating the pres-
sure member and button-head clamp-jaw,
and means for actuating said rock-lever.

6. In a sewing machine, the combination
70 with stitch-forming mechanism including a
reciprocating needle, of a support perma-
nently sustained in substantially fixed angu-
lar relation with said needle and having in
angular relation a work-supporting surface
75 and button-head seat with adjacent button-
shank cavity, a presser-foot overlying and
disposed in clamping relation with the
work-supporting surface of said support,
and a button-head clamp-jaw movable to-
80 ward and from and transversely of said but-
ton-head seat.

In testimony whereof I have signed my
name to this specification in the presence of
two subscribing witnesses.

HERBERT CORRALL.
